DESIGN FOR A TABLE TOP OR SIMILAR ARTICLE

Birdes Faggin, Arlington, Va.

Application May 6, 1944, Serial No. 113,508

Term of patent 14 years

(Cl. D33—14)

To all whom it may concern:

Be it known that I, Birdes Faggin, a citizen of the United States, residing at Arlington, in the county of Arlington, and State of Virginia, have invented a new, original, and ornamental Design for a Table Top or Similar Article, of which the following is a specification, reference being had to the accompanying drawing, forming part thereof.

Figure 1 is a view in top plan of a table top or similar article embodying my new design, the lines indicating contrasting colors; and

I claim:

The ornamental design for a table top or similar article, substantially as shown and described.

BIRDES FAGGIN.
